UNITED STATES PATENT OFFICE.

HARRY L. EIGENBROT, OF SAN FRANCISCO, CALIFORNIA.

ADJUSTABLE VISE-LOCKING SCREW.

Application filed March 5, 1923. Serial No. 622,999.

To all whom it may concern:

Be it known that I, HARRY L. EIGENBROT, a citizen of the United States, and a resident of San Francisco, county of San Francisco, State of California, have invented a new and useful Adjustable Vise-Locking Screw, of which the following is a specification.

The present invention relates to improvements in vise locking screws such as are used for typesetting machines, in machines of this character as used on the market at the present time a vise frame is pivoted to the main frame in such a manner that an upper horizontal member of the vise frame may be brought into contact with a stationary member running substantially parallel to the same and may be locked to the stationary member by means of a pin 10 threadedly engaging the movable member adapted to engage a recess in the stationary member and to be interlocked with the same by means of flanges brought into registry by a turning motion of the pin, the turning motion serving at the same time to draw the two members together. My invention has particular reference to this pin. As constructed at the present time it is made of one piece and it frequently happens that the 15 flange on the pin by means of which the locking engagement is effected is disposed on the pin in such a position that the turning motion does not bring about a full engagement of the two flanges. This again very often causes the flange to break since 20 all the strain is put on a small portion of the same. My invention contemplates the providing of means which allow the position of the flange relative to the winding of the thread to be adjusted in such a manner that a full engagement between the two flanges can always be effected. This construction offers the further advantage that the two flanges can be engaged with one 25 another without the necessity of filing down or fitting one of them if the flange on the pin is not exactly in the correct position relative to the winding of the thread. A further object of my invention is to make 30 the member connecting the flange detachable so that the same can be readily removed in case the flange breaks or is otherwise damaged. Further objects and advantages of the invention will appear as the specification proceeds.

The preferred form of the invention is illustrated in the accompanying drawing in which Figure 1 is a side view illustrating the general arrangement of the vise frame, Figure 2 a front view of the same, Figure 3 an enlarged detail view showing the pin in side elevation, Figure 4 a longitudinal section through the pin, Figure 5 a side view of a member forming one of the parts of the pin, Figure 6 an end view of the same, Figure 7 an end view of the top of the pin carrying the flange, Figure 8 a side view of the same, Figure 9 a longitudinal section through a sleeve used in my pin, Figure 10 a longitudinal section through another sleeve forming part of my pin, Figure 11 an end view of the same, Figure 12 a modified arrangement by means of which the same object may be substantially obtained, Figure 13 a side view of a bushing used in the modified arrangement, Figure 14 an end view of the same and Figure 15 a detail view partly in section showing means for connecting a handle to the pin. While I have shown only the modified form of the invention it should be understood that various changes or modifications may be made within the scope of the claims here-to attached without departing from the spirit of the invention.

The assembled vise frame (1), the particular construction of which is not of interest as far as the present invention is concerned, is pivotally supported as shown at (2) to a stationary frame (3) and is adapted to be swung into parallel relation with the stationary frame and to be secured thereto by means of two pins (4) having flanges (6) thereon adapted to interlock with flanges (7) extending into recesses (8) in the stationary frame (3). Each pin (4) is threaded exteriorly as shown at (9) to engage registering threads in the pivoted vise frame. This locking means thus far described is in common use at the present time but presents several inherent shortcomings which detract from the usefulness of the same. The whole pin as at present constructed is made of one piece so that the flange (6) which covers only about one half of the circumference of the pin as shown in Figure 7 occupies a definite position relative to the winding of the thread (9) which cannot be altered. The particular position of the thread (9) within the vise frame is dependent upon the wind-

ing of the internal thread in the latter frame and it is extremely difficult to dispose both of the windings in such a manner that the flange (6) is in the right position at the 5 right time for interlocking with the flange (7) of the stationary frame (3). This may be the cause of two difficulties. Firstly, the position of the various members may be arranged so as not to allow of a full engagement 10 of the two flanges (6) and (7) so that the actual work of drawing the two frames together and holding them in said position has to be performed by small portions of the two flanges instead of by the whole flange 15 which of course would tend to cause the flanges to break. Secondly, the flange (6) may occupy a position relative to the windings of the threaded engagement that it does not allow of engagement with the flange (7) 20 at all in which case it becomes necessary to grind off the edges whereby the engagement necessarily is weakened.

In the present invention it is proposed to construct the pin in such a manner that the 25 relative position of the flange (6) to the windings of the thread (9) may be adjusted so that a full engagement between the flanges (6) and (7) may be obtained. For this purpose I construct the pin (4) of two 30 principal parts, one carrying the thread and the other carrying the flange and both being adapted to be adjusted in their relative position to one another. These two parts are the sleeve (11) and the flange supporting 35 member (12) adapted to be slidably received within the sleeve (11). A portion of the member (12) is formed of angular cross section as shown at (13) to engage a registering portion of the sleeve whereby the member (12) is prevented from rotating within 40 the sleeve while its position relative to the sleeve may be adjusted. The member (12) is provided with two threaded extensions (14) and (16), the threads of which preferably run in a direction opposite to that of the main thread (9), that is if the latter is a right hand thread the two threads (14) and (16) are left hand. The thread (14) is adapted to receive the tip (17) having the 45 flange (6) secured thereto. It should be noted that this also is an important part of my invention. As made at the present time when the flange (6) breaks a new pin has to be substituted while with my invention the 50 tip only need be renewed. If it should be necessary that the tip should be held against removal on a right hand turn of the pin a set screw (18) may be introduced through its extreme end to engage the reduced end of 55 the member (12), the hole receiving the set screw being countersunk.

The other reduced end (16) of the member (12) is adapted to receive a sleeve (21) which is held against removal by means of a 60 left hand turn by the left hand thread and

secured against removal by a right hand turn by means of a set screw (22) engaging the far end of the member (16). To facilitate the handling of the pin a handle (23) is introduced transversely in the sleeve (21) 70 and held against removal by means of the head (24) at one end and a screw (26) at the other end, the head of which exceeds in diameter the thickness of the handle. Since it is desirable that the handle remain in any 75 position in which it is left by the operator I introduce a split sleeve (27) which yieldingly engages the same and is held against longitudinal motion by the wall of the sleeve (21). 80

The device thus far described works as follows. After the pin has been assembled in the manner shown in Figures 3 and 4 it is threadedly engaged with the pivoted vise frame in the manner shown in Figure 85 1. After the threaded engagement has been carried sufficiently far to allow the flange (6) to catch behind the flange (7) on a rotary motion of the pin the latter is drawn backwards by a turn to the left which causes 90 the flange (6) to engage the flange (7) and to thereby draw the pivoted vise frame (1) in close contact with the stationary frame (3). If the position of the flange (6) at 95 this time should be found to be such that it does not fully engage with the flange (7) the pin may be taken apart by disengaging the member (12) from the sleeve (11) and re-inserting it in a different position. If the flange (6) should break away 100 due to any wear the tip (7) may be taken off and replaced by a new one.

It should be understood that the idea forming the principal part of this invention may be carried out in different ways as 105 for instance by the use of the arrangement shown in Figures 12 to 14. In this case a bushing (29) is provided in the vise frame (1) to threadedly engage the threaded portion (33) of the pin (34) which latter may 110 be made of a single piece. The bushing is rotatable in the vise frame and may be adjusted to any desired position within the same by means of a set screw (31) threadedly engaging the end of the member (3) 115 and passing through one of a plurality of circumferentially arranged perforations (36) in the flange (37) of the bushing. By adjusting the bushing the threaded engagement of the pin with the bushing may be 120 adjusted to bring about a proper engagement of the flange (32) on the pin with the flange (28) of the stationary member (3).

I claim:

1. In a device of the character described, 125 a threaded sleeve member having means associated therewith for advancing the same by rotary motion, a second member adapted to be rendered active by said motion and an operative connection between the two mem- 130

bers allowing the position of the second member to be adjusted relative to the winding of the thread of the sleeve member.

2. In a device of the character described, 5 a threaded sleeve member having means associated therewith for advancing the same by rotary motion, a second member slidably engaging the same adapted to be rendered active by said motion and an operative connection between the two members allowing the position of the second member to be adjusted relative to the winding of the sleeve 10 thread comprising angularly arranged engaging faces.

15 3. Means for locking a movable element to a stationary element comprising a recess in the latter element having a flange extending into the same and a pin threadedly engaging the movable element having a tip 20 removably secured thereto with a flange at the end of the tip adapted to engage the flange in the recess on a turning motion of the pin whereby the two elements are drawn together.

25 4. Means for locking a movable element to a stationary element comprising a recess in the latter element having a flange extending into the same and a pin threadedly engaging the movable element having a tip 30 removably secured thereto with a flange at the end of the tip adapted to engage the flange in the recess on a turning motion of the pin whereby the two elements are drawn together, the pin being constructed to allow 35 the position of the tip flange to be adjusted relative to the winding of the pin thread.

5. Means for locking a movable element to a stationary element comprising a recess in the latter element having a flange extending into the same and a pin threadedly engaging the movable element having a tip 40 removably secured thereto with a flange at the end of the tip adapted to engage the flange in the recess on a turning motion of the pin whereby the two elements are drawn together, the pin comprising a threaded 45 sleeve and a tip engaging member slidably received therein having angularly arranged faces engaging registering faces of the 50 sleeve member.

6. Means for locking a movable element to a stationary element comprising a recess in the latter element having a flange extending thereinto, a pin threadedly engaging the 55 movable element having a tip secured thereto with a flange at the end of the tip adapted

to engage the flange in the recess on a turning motion of the pin whereby the two elements are drawn together, means embodied in the pin for allowing the position of the 60 tip flange to be adjusted relative to the winding of the thread, and means associated with the pin for rotating the same.

7. Means for locking a movable element to a stationary element comprising a recess in the latter element having a flange extending thereinto, a pin threadedly engaging the movable element having a tip secured thereto with a flange at the end of the tip adapted 70 to engage the flange in the recess on a turning motion of the pin whereby the two elements are drawn together, means embodied in the pin for allowing the position of the tip flange to be adjusted relative to the winding of the thread, and means associated with the pin for rotating the same, comprising 75 the pin for rotating the same, comprising an element threadedly engaging its end and a transverse member slidable in the element.

8. Means for locking a movable element 80 to a stationary element comprising a recess in the latter element having a flange extending thereinto, a pin threadedly engaging the movable element having a tip secured thereto with a flange at the end of the tip adapted to 85 engage the flange in the recess on a turning motion of the pin whereby the two elements are drawn together, means embodied in the pin for allowing the position of the tip flange to be adjusted relative to the winding 90 of the thread, and means associated with the pin for rotating the same, comprising an element threadedly engaging its end and a transverse member slidable in the element, having yielding means associated therewith 95 for holding the transverse member in any desired position.

9. Means for locking a movable element 100 to a stationary element comprising a recess in the latter element having a flange extending thereinto, a pin threadedly engaging the movable element having a tip secured thereto with a flange at the end of the tip adapted to engage the flange in the recess on a turning motion of the pin whereby the two elements are drawn together and means allowing 105 the position of one of the flanges to be adjusted relative to the winding of the thread whereby a more perfect engagement between the flanges is secured.

HARRY L. EIGENBROT.
